UNITED STATES PATENT OFFICE.

JOSEPH T. HAMMICK, OF RHINEBECK, NEW YORK.

CAR-COUPING.

SPECIFICATION forming part of Letters Patent No. 243,251, dated June 21, 1881.

Application filed March 24, 1881. (No model.)

To all whom it may concern:

Be it known that I, JOSEPH T. HAMMICK, of Rhinebeck, in the county of Dutchess and State of New York, have invented new and useful Improvements in Car Couplers and Detachers, of which the following is a specification.

Figure 1 is a longitudinal sectional elevation. Fig. 2 is a sectional plan on the line $x x$, Fig. 1. Fig. 3 is a front elevation of the body of the car, showing the cords which operate the detaching-lever and the retaining-pawl. Fig. 4 is an elevation, showing the retaining-pawl holding the operating-lever in the position shown in dotted lines, Fig. 1.

Similar letters of reference indicate corresponding parts.

The object of my invention is to provide improved car coupling and detaching devices, by means of which cars may be coupled and uncoupled without going between them by using the ordinary link, either straight or crooked.

My invention consists, first, in the peculiar arrangement of parts within the draw-head, whereby the tension or force is so distributed that a forward sliding head, which eventually holds the coupling-link up to the coupling-pin, is impelled forward with less power than an additional sliding head which is behind it, both sliding heads being supported and guided on the same rods, which are firmly secured in the front and back ends of the draw-head; and, second, in the arrangement, in combination with a projection formed upon the draw-head to hold the coupling-pin in readiness to fall by its own gravity, of a lever fulcrumed at the top of the car and connected with said coupling-pin by a system of chains or cords conducted to each side of the car, whereby the coupling-pin may be withdrawn from the draw-head and held so that it may replace itself by its own gravity, means being also provided whereby said lever may be retained in place after the withdrawal of the coupling-pin, the whole arrangement of my improvement being such that the coupling-link may be easily forced entirely within the draw-head and preserved from injury.

I more particularly describe my invention as follows:

The drawings, Fig. 1, represent at C the section of one end of an ordinary box or freight car with my improvements connected therewith.

The draw-head A consists of a strong box or frame having a tapering hole in its front, as at A', to permit the entrance of the coupling-link L, and also provided with openings through its top and bottom, through which the body of the coupling-pin passes. Two strong rods, $a a$, 60 are securely fastened in the front and back ends of the draw-head, and serve, first, to strengthen the entire draw-head; second, to support the sliding head F, which is formed of the rectangular frame-work $b c d e$, and in which the central pin, B, is fixed, on which pin B the spring D is supported. The tongue t is fastened rigidly in the plates b and c, and slides in a recess cut in the top of the back or secondary sliding head, E, between which and the head-piece b the spring D is compressed. The said tongue t thus acts to help guide the longitudinal movements of the sliding heads E and F, and also affords a rest for the lower end of the coupling-pin when it is withdrawn, 75 as in dotted lines in Fig. 1. The sliding head E is also supported and guided on the stay-rods $a a$, and a pair of springs, G G, loosely coiled on the rods $a a$, are compressed between the back end of the draw-head and the back of the head 80 E, as shown. Retaining cords or chains o limit the forward movement of said head E.

In the drawings, Figs. 1 and 2, the front sliding head, F, is shown partially slid back and holding the link L in place by the coupling-pin P. It will be understood that when the link L is not so confined in the draw-head the spring D will force the head F up to the inner face of the front end of the draw-head A. The spring D offering much less resistance 85 to the backward sliding of the front head, F, on the forcible entrance of the coupling-link into the draw-head than the two springs G offer against a sliding movement of the secondary head E, it is evident that said front head, F, 90 will first slide back on the entrance of said coupling-link and compress the spring D only, the sliding movement of the head F being sufficient to admit of coupling the cars without requiring a backward-sliding movement of the 95

secondary head E; but when, in the act of coupling cars or switching them, the cars should come in violent contact with each other or with any obstacle, the secondary sliding head E will 5 be also forced backward by the head F until the coupling L is forced entirely within the draw-head A. Said link L is thus always protected from injury.

I describe my improved detaching apparatus as follows:

A projection, M, of proper height is formed upon the front of the draw-head A, so that it shall embrace the body of the coupling-pin and prevent its entire withdrawal from the draw-head by the limited movement of the lever N. A chain or cord, V, connects the head P' of the coupling-pin with said lever N, which is suitably fulcrumed in a standard, N', on the top of the car. The other end of lever N is 20 connected, as at R, with the cords r, which are carried down through the car-roof and diverged to both sides of the car, as in Fig. 3, where they pass through suitable guiding-staples, S, terminating below with proper 25 handles or rings S', which afford means for pulling down the back end of the lever N and raising the coupling-pin P, as in dotted lines, Fig. 1, from either end or side of the car, the projection M meanwhile holding the coupling-pin in readiness to again fall in place, as in 30 full lines, by its own gravity. When the parts are in the relative positions shown in dotted lines the retaining-rings T on the cords r can be slipped over the staples S, or other hooks 35 or knobs specially provided for the purpose, and the coupling-pin will be held withdrawn in case it is not desired to couple the cars.

I have also provided means whereby the lever N may be secured with its end R depressed, and again released from the platform or from either side of the car, which means consist of the pawl n, pivoted to the upright N', and having attached to it the cord n', which passes through the car-roof, and may hang 45 vertically over the platform, as in Fig. 3, or be connected with diverging cords n', as in Fig. 1, said cords passing through guiding-staples

n', which latter arrangement admits of releasing said pawl n from either side of the car.

My improved coupler and detacher may be 50 applied to any ordinary build of freight-cars without compelling an alteration of its framework. Any ordinary style of coupling-link may also be used, be said links either longitudinally straight or crooked, as when coupling cars whose bumper-beams or draw-heads 55 do not meet in the same horizontal plane.

My apparatus is shown in the drawings in a crude form, as made of wood principally. It should be made principally or wholly of 60 metal, in which case ample strength may be secured with minimum weight.

It is obvious that my apparatus above described may be operated to couple or uncouple cars to which it is applied, or secured against 65 any coupling action of the cars, either by the direct operation of the lever N, by a railroad attaché on the roof of the cars, or by the operation of said lever N through the medium of the connected cords r and n' from either side of 70 the cars, without going between them, whereby the constant loss of life and limb of railway employés may be avoided.

Having thus fully described my invention, I claim as new and desire to secure by Letters 75 Patent—

1. The combination, in a car-coupling, with the draw-head A, of the rods a a, the sliding head F, carrying central pin, B, the spring D, the sliding head E, the tongue t, fastened rigidly in plates b c, the springs G, and the cords o o, as shown and described.

2. In combination with the secondary sliding head E, the retaining-cords o, substantially as and for the purpose described.

3. In combination, with the lever N, the pawl n, provided with a cord or cords, n', substantially as and for the purposes herein specified.

JOSEPH T. HAMMICK.
